UNITED STATES PATENT OFFICE

LOUIS STIENNON, OF NEW HAVEN, CONNECTICUT, ASSIGNOR, BY MESNE ASSIGNMENTS, TO WINCHESTER REPEATING ARMS COMPANY, OF NEW HAVEN, CONNECTICUT, A CORPORATION OF MARYLAND

SINGLE-TRIGGER MECHANISM FOR MULTIPLE-BARREL FIREARMS

Continuation of application Serial No. 470,412, filed July 24, 1930. This application filed September 23, 1931. Serial No. 535,535.

This application constitutes a continuation of application Serial No. 470,412, filed July 24, 1930, allowed August 3, 1931, and abandoned for the sole purpose of permitting the present application to be substituted therefor.

This invention relates to an improvement in trigger-mechanisms for multiple-barrel firearms and relates in particular to an improvement in that class of trigger-mechanisms in which a single trigger serves to release two or more firing-mechanisms in selective sequence.

The main object of this invention is to provide a simple, strong and compact trigger-mechanism of the type referred to, constructed with particular reference to safety and reliability and convenience of operation.

Another object of this invention is to provide a single-trigger mechanism of the type referred to, with simple, reliable and conveniently-located means for selecting the firing sequence of the barrels so that the user of the firearm can readily understand the operation thereof.

I am aware that it has heretofore been proposed to mount a selector or control-member for a single-trigger mechanism in the trigger of a firearm, but such previous mechanism, while theoretically advantageous, has been open to the serious objection that its manual operation required the exertion of pressure of such character upon the trigger itself as would cause the accidental discharge of the arm unless the user took the exceptional precaution of first throwing on the safety mechanism (if such were part of the gun mechanism), and subsequently, after having made the selection of firing order, remembering to throw the safety mechanism off. The result has been that a single-trigger firearm, equipped with such a selector mechanism, would have been very dangerous and could be rendered reasonably safe only by the unfailing attention of the user and the religious performance of the ritual of throwing the safety mechanism into engagement before attempting to reverse the firing sequence and then retiring the safety mechanism before the arm could become avail-

able for firing. Usually, a choice of firing order must be made at the instant of sighting the game and it goes without saying that if the user must first go through the complicated steps above outlined, the game would 55 usually escape.

A further and important object of my invention, therefore, is to provide a single-trigger mechanism having a manual control- or selector-means with the advantages due to being mounted upon the trigger itself, such as convenience of operation, unmistakability of purpose and ease of ascertainment of position by sight or feeling, yet so located that it may be operated without endangering the 60 premature discharge of the arm due to pressure in a direction normal to the firing movement of the trigger, or interfere with the free insertion of the finger for firing.

With the above and other objects in view as 70 will appear from the following, my invention consists in a single-trigger mechanism for multiple-barrel firearms, having certain features of construction and arrangements of parts as will be hereinafter described and 75 particularly recited in the claims.

In the accompanying drawings:

Fig. 1 is a broken view partly in side elevation and partly in vertical longitudinal section of the frame-portion of a double-barrel shotgun embodying my invention, together with the parts associated therewith and showing the parts in the positions due to them when both the firing-mechanisms are in their 80 cocked positions;

Fig. 2 is a view corresponding to Fig. 1, but showing the parts in the positions due to them after the trigger has been pulled and the right-hand firing-mechanism has been 85 released, but before the rearward draft upon the trigger has been relaxed;

Fig. 3 is a corresponding view, but showing the parts in the positions due to them after the initial rearward draft upon the 90 trigger has been relaxed, and with the parts in the positions in readiness to release the left-hand firing-mechanism;

Fig. 4 is a transverse sectional view taken 95 on the line 4—4 of Fig. 1;

Fig. 5 is a broken view in horizontal section taken on the line 5—5 of Fig. 1;

Fig. 6 is a broken detail view looking downward upon the sear-actuator and the rear ends of the respective sears;

Fig. 7 is an enlarged-scale detached perspective view of the selective sear-actuator;

Fig. 8 is a similar view of the trigger and the trigger-blade organized therewith; and

Fig. 9 is a corresponding view of the manually-operable selector-button.

In the main figures of the accompanying drawings, I have illustrated the firing-mechanisms and associated parts of a double-barrel break-down shotgun, though it will be understood that my invention is applicable to various types of multiple-barrel firearms.

In the embodiment of my invention herein chosen for illustration, I employ a frame 20 formed at its upper rear end with a rearwardly-extending tang 21 and having secured to its under face a trigger-plate 22 between the upper face of the rear end of which latter and the under face of the tang 21, is secured the forward end of a butt-stock 23. A relatively-long screw 24 extends upward between the rear end of the trigger-plate 22 aforesaid and the rear end of the tang 21 of the frame 20, and serves to anchor the butt-stock 23 in place in conjunction with a screw 25 extending downward through the forward end of the tang 21 and into the upper end of a so-called "lump" 26, formed integral with and upstanding from the trigger-plate 22 already referred to.

The butt-stock 23 above referred to is cut away to clear the mechanism about to be described and is provided near its forward end with a bushing 27 positioned so as to bear at its lower end against the upper face of the lump 26 and at its upper end against the under side of the tang 21 and providing a passageway for the screw 25, already referred to.

Pivotedly mounted within the forward end of the frame 20 are a pair of corresponding hammers 28 and 29 respectively provided at their forward upper ends with firing-pins 30 and 31, and in their lower rear walls with sear-notches 32 and 33. The said hammers 28 and 29 are also formed at their lower ends, adjacent their sear-notches, respectively, with cam-like heels 32^a and 33^a.

The hammers 28 and 29, just above referred to, are mounted upon a transverse pivot-pin 34, mounted in the frame 20, and are respectively formed with notches 35 and 36 receiving pins 37 and 38 of hammer-operating links 39 and 40, in the usual manner of firearm construction, it being understood that the links 39 and 40 exert a constant effort upon their respective hammers 28 and 29 to swing the upper ends of the same forward into their firing positions.

The sear-notch 32 of the right-hand ham-

mer 28 coacts with the forward end of a horizontally-arranged sear 41, mounted about midway of its length for oscillation upon a transverse pin 42 in the frame 20. The rear end of the right-hand sear 41 is provided with an inwardly-projecting finger 43 adapted to be lifted by what I shall, for convenience, designate as an upwardly-facing "first-stage" sear-actuating ledge 44, formed upon a transversely-shiftable and longitudinally-oscillating sear-actuator 45.

The sear-actuator 45, just above referred to, is formed with a depending-tang or blade 46, narrower than the body-portion proper thereof, and formed in its lower end with a downwardly-opening notch 47, entering an annular groove 48 formed midway in a reciprocating selector-button 49 and embracing the reduced central portion 50 of the said button, resulting from the formation of the said annular groove 48. The blade 46 is located in an upwardly-opening longitudinal groove 51 formed in a trigger 52, while the selector-button 49 is mounted for axial movement in a direction transverse to the major axis of the gun in a bore 53 formed in the said trigger within the profile of the finger-piece thereof and intersecting the groove 51 aforesaid.

It will be seen from the foregoing that the sear-actuator 45 is mounted upon the reduced central portion 50 of the selector-button 49 with capacity for swinging movement forward and back and that by virtue of the fact that its notched lower end is entered into the annular groove 48 in the said selector-button 49, it will participate in any movement of the latter in a direction cross-wise of the gun, as will hereinafter appear.

To provide for normally exerting a constant effort to swing the upper end of the sear-actuator 45 forward and to yieldingly hold the same, together with the button 49, in either of its two positions of lateral adjustment, as will hereinafter appear, I provide the forward edge of the blade 46 thereof with an upwardly-facing wedge-shaped detent-nose 54, the opposite sloping faces of which are alternately engaged by the rearwardly-extending arm 55 of a torsion-spring 56, which latter is also provided with a forwardly-extending arm 57 located in a horizontal groove 58 formed in the trigger 52 and intersecting a transverse bore 59 also formed in the said trigger and in which the coil-portion of the spring 56 is located.

The arm 55 of the spring 56 plays up and down in a vertical guide-slot 60 extending between the bore 59 and the upwardly-opening longitudinal groove 51 of the said trigger, in which the lower end of the blade 46 of the sear-actuator is located.

As before pointed out, the sear-finger 43 of the right-hand sear 41 is adapted to coact with the upwardly-facing first-stage sear-

actuating ledge 44 of the sear-actuator, which is curved, as shown, to conform to an arc swung about the center of the selector-button 49, as is also a right-hand second-stage sear-actuating ledge 62 which is located to the rear and to one side of the aforesaid first-stage ledge 44, as clearly shown in Fig. 7 of the drawings, and forms the upper surface of a horizontal rib 62^a laterally offsetting from the right-hand side of the sear-actuator 45.

The opposite side of the sear-actuator 45 is also formed with a left-hand second-stage sear-actuating ledge 63 forming the upper surface of a complementary rib 63^a and is adapted to coact with the under-face of the inwardly-turned sear-finger 64 forming a feature of the left-hand sear 65 which, like the right-hand sear 41 already referred to, is mounted for oscillating movement upon the transverse pin 42 and has its forward end coacting with the sear-notch 33 of the left-hand hammer 29 before referred to.

Returning now to the trigger 52, the same is mounted for pivotal movement upon a transverse pin 66 extending crosswise through the lump 26 of the trigger-plate 22, which latter, together with a portion of the lump 26, is formed with a vertical longitudinal clearance-slot 67 in which the said trigger plays.

The upper forward portion of the trigger 52 is provided with an upwardly-opening groove 68 receiving the forward end of a trigger-blade 69 through which the pivot-pin 66 already referred to passes, so that the said blade, to all intents and purposes, forms an integral part of the trigger 52.

To yieldingly hold the finger-piece 70 of the trigger 52 in its normal forward position, as shown in Fig. 1, I employ a plunger 71, the rear end of which engages with the forward edge of the trigger-blade 69 under the urge of a helical spring 72 mounted in a rearwardly-opening pocket 73 formed in the lump 26 and in which the said plunger 71 is adapted to reciprocate.

The rear- and under-face of the rear end of the trigger-blade 69 is adapted to coact with a pivotal inertia-weight 74 as will hereinafter appear, which is mounted upon a transverse pivot 75 in the trigger-plate 22 and is normally held in its rearward or re-tired position by a plunger 76 engaging the upper surface of the said trigger-plate adjacent the pivot-pin 75 and reciprocating in an inclined bore 77 in the said inertia-weight and urged outward by a helical spring 78 also located in the said bore 77 thereof.

The upper edge of the rear portion of the trigger-blade 69 is adapted to coact on occasion with the under-face of a reciprocating safety-rod 79 and also to enter a vertical longitudinal clearance-slot 80 formed therein, as will hereinafter appear. The forward

end 81 of the said safety-rod is of cylindrical form and reciprocates in a longitudinal passage 82 formed in the lump 26.

Intermediate its ends, the safety-rod 79 above referred to is formed with a bifurcated 70 depending resetting finger 83 adapted to coact with a re-setting lug 84 upwardly-extending from the sear-actuator 45 and is pivotally secured at its rear end by means of a pivot-pin 85 to a substantially-vertical safety-lever 75 86 mounted for oscillation forward and back upon a pin 87 extending transversely through the trigger-plate 22, near the rear end thereof.

The rear end of the inertia-weight 74 is 80 formed with a clearance-notch 88 for the clearance of the lever 86, the upper end of which latter is entered into a downwardly-opening notch 89 formed in a safety-slide 90 sliding longitudinally upon the upper face of the tang 21 of the frame 20 in the usual manner of safety mechanisms. A detent-spring 91 is carried by the said slide and formed at its forward end with an upwardly-extending hump 92 adapted to enter either 90 one of two detent-notches 93 or 94 to retain the said slide in either one of its two positions.

The forward end of the cylindrical portion 95 81 of the safety-rod 79 is adapted to be engaged by the rear face of a locking-bolt 95 in the usual manner of breakdown-firearms. The operation and construction of locking-mechanisms is so well understood in the art 100 that it is believed that no further description is required other than to say that the said locking-bolt 95 is retracted in the usual manner by a finger 96 depending from a head 97 mounted upon the lower end of the shank 98 of a laterally-swinging top-lever 99 which effects the unlocking of the piece for breakdown action in the usual manner of breakdown firearms.

The finger-piece 70 of the trigger 52 is 110 guarded in the usual manner by a trigger-bow 100 mounted upon the under-face of the trigger-plate 22, as clearly shown in Figs. 1, 2 and 3 inclusive.

Let it be supposed that the user desires to fire the right barrel of the gun first, in which 115 case the gun will be cocked and the parts will occupy the positions in which they are shown in Figs. 1, 4, 5 and 6.

By reference to the figures just above referred to, it will be seen that both hammers are in their cocked positions and that the selector-button 49 has been manually forced from left to right, and held in such right-hand position by the engagement of the arm 120 55 of the spring 56 with the left-hand slope of the detent-nose 54. This action brings the first-stage sear-actuating ledge 44 beneath the sear-finger 43 of the right-hand sear 41 and hence removes the said ledge from beneath the sear-finger 64 of the left-hand sear 130

65, though it will be noted by reference to Fig. 6 in particular that the left-hand second-stage sear-operating ledge 63 is in line with and slightly below the left-hand sear-finger 64, though to the rear thereof, in readiness to be swing forward by the arm 55 of the spring 56, beneath the said finger after the right-hand sear has been actuated, as will be presently described.

With the parts in the positions as just described, a rearward draft upon the finger-piece 70 of the trigger 52 will cause the latter to swing upon its pin 66 and lift the sear-actuator 45, with the effect of engaging the first-stage sear-actuating ledge 44 thereof with the under-face of the sear-finger 43 of the right-hand sear 41, and thus swing the latter so as to disengage its forward end from the sear-notch 32 in the right-hand hammer 28. The right-hand hammer will thus be permitted to swing forward in the usual manner of firearms to fire the cartridge in the right-hand barrel (not shown).

In swinging into position to fire a cartridge, the right-hand hammer 28 will act through its cam-like heel 32^a to depress the forward end of the right-hand sear 41, thus lifting the finger 43 thereof above the right-hand rib 62^a so that the sear-actuator is temporarily prevented from swinging forward into position to actuate the left-hand sear only by the engagement of the forward wall 102 of its left-hand rib 63^a with the left-hand sear-finger 64.

The swinging movement of the trigger, as above described, will be limited by the engagement of the projecting end of the selector-button 49 with the under face of the trigger-plate 22 adjacent the slot 67 therein. The parts will now have assumed the positions in which they are shown in Fig. 2.

When the right-hand barrel has been fired as just above described, the recoil of the firearm will cause the pivotal inertia-weight 74 to assume the position in which it is shown by broken lines in Fig. 2, in which position its periphery is interposed beneath the rear end of the trigger-blade 69, thus temporarily blocking the return of the trigger to its normal position until the rebound or counter-recoil of the gun takes place, at which time the said inertia-weight will be returned by the combined action of the counter-recoil and its spring 78 to the position indicated by full lines.

The action of the inertia-weight just above described serves at this time to prevent the forward movement of the trigger 52 into position for actuating the left-hand sear 65 as an incident to the recoil of the arm and therefore forestalls an involuntary second rearward movement of the trigger and the consequent unintentional firing of the second barrel as a result of the counter-recoil.

The right-hand barrel having been fired

as just above described and the recoil and counter-recoil having expended their force, the user deliberately relaxes rearward draft upon the finger-piece 70 of the trigger 52 to permit the said finger-piece to swing forward under the urge of the trigger-spring 72. This forward or return movement of the trigger lowers the sear-actuator 45 sufficiently to disengage the forward wall of its left-hand rib 63^a from the rear end of the left-hand sear-finger 64 and thus permit the said sear-actuator to swing forward under the urge of the arm 55 of the spring 56 to interpose the left-hand second-stage sear-actuating ledge 63 beneath the sear-finger 64 of the left-hand sear 65. The parts will now occupy the positions in which they are shown in Fig. 3 in readiness to release the left-hand hammer 29 for firing the left-hand barrel (not shown).

The parts having assumed the positions in which they are shown in Fig. 3, a subsequent rearward draft upon the finger-piece 70 of the trigger 52 will lift the sear-actuator 45 and cause its left-hand second-stage sear-actuating ledge 63 to engage the underside of the left-hand sear-finger 64 and thus lift the same, with the effect of rocking the left-hand sear 65 to disengage its forward end from the sear-notch 33 of the left-hand hammer 29, thereby effecting the firing of the left-hand barrel (not shown). The inertia-weight 74 will operate in the same manner under the action of the recoil and counter-recoil of the firearm, as previously described.

When the user wishes to re-load the arm, he will swing the top-lever 99 laterally to retract the locking-bolt 95, and "break" the piece, thus effecting the cocking of both of the hammers 38 and 29, all in the well-known manner of breakdown-firearms.

When the locking-bolt 95 is retracted as just above described, it will force the safety-rod 79 rearward, with the effect of causing the re-setting-finger 63 thereof to engage the re-setting-lug 84 of the sear-actuator, thus returning it to the position in which it is shown in Fig. 1, and with the further effect of moving the safety-slide 90 rearward and moving the clearance-slot 80 of the said safety-rod out of registration with the trigger-blade 69, so that the trigger cannot be swung for firing the gun.

When the user is ready to fire the gun, he manually moves the safety-slide 90 forward, thereby bringing the clearance-slot 80 of the safety-rod 79 into registration with the rear end of the trigger-blade 69, so that the trigger may be operated when desired.

In the foregoing description of operation, I have described my improved trigger-mechanism as set to release the hammers 28 and 29 in the order "right-left," but it will be seen that if the user of the arm chooses to reverse the firing order, namely, to "left-right," he has but to apply a lateral pressure

upon the selector-button 49 to move the same, together with the sear-actuator 45, to the limit of its left-hand movement, in which position the first-stage sear-actuating ledge 44 of the said sear-actuator will be interposed beneath the left-hand sear-finger 64 and removed from beneath the right-hand sear-finger 43. With the parts thus set, when the first pull is exerted upon the finger-piece 70 of the trigger 52, the left-hand hammer 29 will be released in the same manner as that already described in connection with the release of the right-hand hammer, and upon the release of rearward draft upon the finger-piece 70, the parts will automatically adjust themselves so that the right-hand second-stage sear-actuating ledge 62 will be beneath the right-hand sear-finger 43, preparatory to rocking the same for releasing the right-hand hammer 28 when the second rearward draft is imposed upon the finger-piece 70 of the trigger.

From the foregoing it will be seen that a single trigger serves to successively fire both barrels, either in the order "right-left" or "left-right" and that the location of the manually-operable selector-member or button in the trigger itself not only makes for convenience but simplifies the construction and arrangement of the parts and secures a unique certainty of action.

It will be noted that the selector-button 49 is mounted in the trigger 52 above the finger-contact portion thereof, so as not to be affected by nor interfere with the user's finger when the trigger is being pulled, or when the finger is being inserted preparatory to firing the arm. Furthermore, the said selector-button, owing to its novel location above the finger-contact surfaces of the trigger, is operable for selecting the firing sequence solely by pressure exerted crosswise of the trigger and does not require any coincidental upward pressure which might inadvertently fire the arm.

This advantage of being operable solely by lateral pressure is due also in part to the fact that my improved selector-member is sufficiently longer than the width of the immediately adjacent portions of the trigger in which it is mounted to be capable of being thrown fully into either its right- or left-hand position by lateral pressure applied to the appropriate normally projecting end and that, as the said selector-member projects only on the side corresponding with the barrel which will be fired by the first pull of the trigger, it thus provides a convenient visual or tactful indicator of the firing order of the arm.

It will be understood by those skilled in the art that my invention may assume varied physical forms without departing from my inventive concept, and I, therefore, do not limit myself to the specific embodiment here-

in chosen for illustration, but only as indicated in the appended claims.

I claim:

1. In a single-trigger mechanism for multiple-barrel firearms, the combination with a pair of firing-mechanisms; of a trigger; and a manually-shiftable actuator-member carried by the said trigger with capacity for movement both crosswise and longitudinally with respect thereto and engageable with portions of the said firing-mechanisms for releasing the same in a selective sequence when the said trigger is actuated.

2. In a single-trigger mechanism for multiple-barrel firearms, the combination with a pair of firing-mechanisms; of a trigger; and a manually-shiftable actuator-member carried by the said trigger with capacity for bodily movement crosswise with respect thereto and oscillatory movement forward and back in the plane thereof and engageable with portions of the said firing-mechanisms for releasing the same in a selective sequence when the said trigger is actuated.

3. In a single-trigger mechanism for multiple-barrel firearms, the combination with a pair of firing-mechanisms including the respective sears thereof; of a trigger; and a manually-shiftable sear-actuator carried by the said trigger with capacity for movement both crosswise and longitudinally with respect thereto and engageable with the said sears for moving the same to release the said firing-mechanisms in a selective sequence when the said trigger is actuated.

4. In a single-trigger mechanism for multiple-barrel firearms, the combination with a pair of firing-mechanisms including the respective sears thereof; of a trigger; and a manually-shiftable sear-actuator carried by the said trigger with capacity for bodily movement crosswise with respect thereto and oscillatory movement forward and back in the plane thereof and engageable with said sears for moving the same to release the said firing-mechanisms in a selective sequence when the said trigger is actuated.

5. In a single-trigger mechanism for multiple-barrel firearms, the combination with a pair of firing-mechanisms including the respective sears thereof; of a trigger; a manually-shiftable sear-actuator carried by the said trigger with capacity for movement both crosswise and longitudinally with respect thereto and engageable with the said sears for moving the same to release the said firing-mechanisms in a selective sequence when the said trigger is actuated; and a manually-operable reciprocating selector-button mounted in the said trigger with capacity for movement transversely with respect thereto and operatively connected to the said sear-actuator for shifting the same.

6. In a single-trigger mechanism for multiple-barrel firearms, the combination with a

pair of firing-mechanisms including the respective sears thereof; of a trigger; a manually-shiftable sear-actuator carried by the said trigger with capacity for bodily movement crosswise with respect thereto and oscillatory movement forward and back in the plane thereof and engageable with said sears for moving the same to release the said firing-mechanisms in a selective sequence when the said trigger is actuated; and a manually operable reciprocating selector-button mounted in the said trigger with capacity for movement transversely with respect thereto and operatively connected to the said sear-actuator for shifting the same.

7. In a single-trigger mechanism for multiple-barrel firearms, the combination with a pair of firing-mechanisms including the respective sears thereof; of a trigger; a manually-shiftable sear-actuator carried by the said trigger with capacity for movement both transversely and longitudinally thereof, and provided with a first-stage sear-actuating portion located thereon in position to be brought into registration with either of the said sears and out of registration with the complementary sear by a transverse movement, and provided also with a second-stage sear-actuating portion located thereon in position to be brought into registration with the said complementary sear by a movement in a plane longitudinal of the said trigger when the initial pull thereupon is relaxed; and spring-means normally urging the said sear-actuator longitudinally of the said trigger and in a direction to bring the said second-stage sear-actuating portion into registration with the said complementary sear.

8. In a single-trigger mechanism for multiple-barrel firearms as defined in claim 7 and having in combination a recoil-operated member coacting with a portion of the said trigger to temporarily hold the same in its retracted position; whereby the sear-actuator carried by the said trigger is prevented from moving under the urge of the said spring-means into position for operating the second sear until the recoil and counter-recoil of the firearm have expended their forces.

59. 9. In a single-trigger mechanism for multiple-barrel firearms, the combination with a pair of firing-mechanisms including the respective sears thereof; of a trigger; a manually-shiftable sear-actuator carried by the said trigger with capacity for bodily movement transversely thereof and swinging movement longitudinally thereof and provided with a first-stage sear-actuating portion located thereon in position to be brought into registration with either of the said sears and out of registration with the complementary sear by a transverse movement, and provided also with a second-stage sear-actuating portion located thereon in position to be brought into registration with the said com-

plementary sear by a rocking movement in a plane longitudinal of the said trigger; and spring-means normally tending to swing the said sear-actuator longitudinally of the said trigger and in a direction to bring its second-stage sear-actuating portion into registration with the said complementary sear.

10. In a single-trigger mechanism for multiple-barrel firearms, the combination with a pair of firing-mechanisms including the respective sears thereof; of a trigger; a manually-shiftable sear-actuator carried by the said trigger with capacity for movement both transversely and longitudinally thereof, and provided with a first-stage sear-actuating portion located thereon in position to be brought into registration with either of the said sears and out of registration with the complementary sear by a transverse movement, and provided also with a second-stage sear-actuating portion located thereon in position to be brought into registration with the said complementary sear by a movement in a plane longitudinal of the said trigger when the initial pull thereupon is relaxed; spring-means normally urging the said sear-actuator longitudinally of the said trigger and in a direction to bring the said second-stage sear-actuating portion into registration with the said complementary sear; and a manually-operable selector mounted in the said trigger with capacity for movement transversely with respect thereto and operatively connected to the said sear-actuator for shifting the same transversely of said trigger.

11. In a single-trigger mechanism for multiple-barrel firearms, the combination with a pair of firing-mechanisms including the respective sears thereof; of a trigger; a manually-shiftable sear-actuator carried by the said trigger with capacity for bodily movement transversely thereof and provided with a first-stage sear-actuating portion located thereon in position to be brought into registration with either of the said sears and out of registration with the complementary sear by a transverse movement, and provided also with a second-stage sear-actuating portion located thereon in position to be brought into registration with the said complementary sear by a rocking movement in a plane longitudinal of the said trigger; spring-means normally tending to swing the said sear-actuator longitudinally of the said trigger and in a direction to bring its second-stage sear-actuating portion into registration with the said complementary sear; and a manually-operable reciprocating selector-button mounted in the said trigger with capacity for movement transversely with respect thereto and operatively connected to the said sear-actuator for shifting the same transversely of said trigger.

12. In a single-trigger mechanism for multiple-barrel firearms, the combination with a

- pair of firing-mechanisms, including the respective sears thereof; of a trigger; a manually-operable selector-button mounted within the exposed profile of the trigger for transverse reciprocating movement therein; and a manually-shiftable sear-actuator member pivotally mounted for longitudinal rocking movement upon the said selector-button. 5
13. In a single-trigger mechanism for multiple-barrel firearms, the combination with a pair of firing-mechanisms, including the respective sears thereof; of a trigger; a manually-operable selector-button mounted within the exposed profile of the trigger for transverse reciprocating movement therein; and a manually-shiftable sear-actuator member pivotally mounted for longitudinal rocking movement upon the said selector-button and bodily movable transversely therewith. 10
14. In a single-trigger mechanism for multiple-barrel firearms, the combination with a pair of firing-mechanisms including the respective sears thereof; of a trigger; a sear-actuator mounted in the firearm-structure with capacity for both transverse and longitudinal movement with respect thereto; and a spring operatively connected to the said sear-actuator for yieldingly maintaining the same at either limit of its transverse movement and for moving the same longitudinally with respect to the firearm-structure. 15
15. In a single-trigger mechanism for multiple-barrel firearms, the combination with a pair of firing-mechanisms including the respective sears thereof; of a trigger; a sear-actuator carried by the said trigger with capacity for both transverse and longitudinal movement with respect thereto; and a spring operatively connected to the said sear-actuator for yieldingly maintaining the same at either limit of its transverse movement and for moving the same longitudinally with respect to the said trigger. 20
16. In a single-trigger mechanism for multiple-barrel firearms, the combination with a pair of firing-mechanisms including the respective sears thereof; of a trigger; a sear-actuator mounted in the firearm-structure with capacity for both transverse and longitudinal movement with respect thereto; and a torsion-spring operatively connected to the said sear-actuator for yieldingly maintaining the same at either limit of its transverse movement and for moving the same longitudinally with respect to the firearm-structure. 25
17. In a single-trigger mechanism for multiple-barrel firearms, the combination with a pair of firing-mechanisms including the respective sears thereof; of a trigger; a manually-operable selector-button mounted in the said trigger with capacity for transverse reciprocating movement therein; a transversely-shiftable and longitudinally-movable sear-actuator carried by the said trigger and operatively connected to the said selector-but- 30
- ton; and a spring operatively connected to the said sear-actuator for yieldingly maintaining the same at either limit of its transverse movement and for moving the same longitudinally with respect to the said trigger. 70
18. In a single-trigger mechanism for multiple-barrel firearms, the combination with a pair of firing-mechanisms including the respective sears thereof; of a trigger; a sear-actuator carried by the said trigger with capacity for both transverse bodily movement and longitudinal oscillating movement with respect thereto; and a spring operatively connected to the said sear-actuator for yieldingly holding the same at either limit of its transverse movement and for rocking the same longitudinally with respect to the said trigger. 75
19. In a single-trigger mechanism for multiple-barrel firearms, the combination with a pair of firing-mechanisms including the respective sears thereof; of a trigger; a sear-actuator carried by the said trigger with capacity for both transverse bodily movement and longitudinal oscillating movement with respect thereto; and a spring carried by the said trigger and operatively connected to the said sear-actuator for yieldingly holding the same at either limit of its transverse movement and for rocking the same longitudinally with respect to the said trigger. 80
- In testimony whereof, I have signed this specification. 85
